Inventor,
Martin Weaver

United States Patent Office.

MARTIN WEAVER, OF EAST EARL TOWNSHIP, PENNSYLVANIA, ASSIGNOR TO HIMSELF AND PHILIP FOREMAN, OF SAME PLACE.

Letters Patent No. 89,904, dated May 11, 1869.

IMPROVED FEED-REGULATOR FOR MILLS.

The Schedule referred to in these Letters Patent and making part of the same.

To all whom it may concern:

Be it known that I, MARTIN WEAVER, miller, of East Earl township, in the county of Lancaster, and State of Pennsylvania, have invented a new and improved Arrangement for Regulating the Feed for Millstones; and I do hereby declare that the following is a full, clear, and exact description of the construction and operation of the same, reference being had to the accompanying drawings, making a part of this specification, in which—

Figure 1 is an elevation or section of my improvement in place in the eye of the runner G; H, the bed-stone; R, the rhyne; S, the spindle; I, the case; J, a board over the opening of the case, as in common use.

Figure 2, the outer cap or vessel, which sets upon the rhyne, and fills the eye of the stone, or runner G.

Figure 3 shows the inside bottom of the cup A, with the spout-openings a', and central elevated disk B, and raised curved beaters b.

Figure 4 shows the manner in which the spouts or oval tubes a of A enter or pass down between the horns of the rhyne R or its open angles.

Figure 5 shows an inner open ring, D, (nearly of like diameter of the vessel A,) having slotted ears E on two sides, by which it is affixed by binding-screws, and made adjustable on the cross-board J, fig. 1.

Figure 6 shows an ordinary silent feed, in which there is no novelty.

The nature of my invention consists in providing the eye of a millstone, or runner with a device that will prevent the material to be ground from sticking to the sides of the eye or from forming clogs or lumps, as frequently happens, causing the eye to fill and run over, and causing such an increase of speed on the runner as to burst the stone.

To enable others skilled in the art to make and use my invention, a brief explanation, in addition to the descriptive reference of the drawings, will suffice.

The metallic vessel A, with its four spouts a, and bottom, B, are set into the eye of the stone, so as to fill the same from the rhyne to the top surface. The tubes a project obliquely downward between or through the open angles of the cross-bars R of the rhyne to within a short distance of the bed-stone.

A cast-iron ring, D, fig. 5, is set within this outer case or vessel A, allowing only sufficient play for the outer vessel to revolve freely around it. This ring D is stationary, and provided with four (more or less)

flanges or beaters, d, attached to the inner circumference, and extending toward the centre. There are also two elongated ears, E, with an open slot, e, for a binding-screw, by which this ring D is adjusted within the box or case A the desired height from the bottom, B, and attached to a board, J, over the feed-opening in the case I, fig. 1.

The ordinary silent feed F, fig. 6, attached by ears f to the aforesaid board J, and adjusted over the central disk B, may be used with said ring D, or the common damsel in its stead.

The central curved beaters b and the flanges d will agitate the materials, and work them to the several spouts, and convey the same between the runner and bed-stone with certainty, and prevent all danger of clogging, so as to arrest the proper delivery, but, on the contrary, secure a uniform, certain, and regular feed, and thereby obviate the possibility of stones being bursted from a stoppage of the feed, and the extra high speed of the runner induced by being thus suddenly relieved from the necessary supply to keep up the check on the runner.

Having lost several stones by bursting from this cause, I was led to experiment, to prevent such an accident, which resulted in the invention of the device herein set forth, and a test for some months has satisfied me of its value and efficiency.

I am not aware that such a tubulated case A and ring D were ever before used in the manner set forth, either with the ordinary damsel or silent feed.

I do not claim a receptacle situated within the eye of the runner-stone, and provided with lateral or conducting-tubes and an interior cylinder, furnished with wings or beaters, for such is shown in the patent of John Nairn, October 6, 1868; but

What I do claim, and desire to secure by Letters Patent, is—

The combination and arrangement of the external cup A with its conductors a a, central elevated disk B, and curved beaters b b b, internal ring D, provided with flanges d d d and slotted ears E e, all suspended within the eye of the runner G, and operated as and for the purpose herein shown and described.

MARTIN WEAVER.
